UNITED STATES PATENT OFFICE.

ERNEST UNGER, OF NEW YORK, N. Y., ASSIGNOR, BY MESNE ASSIGNMENTS,
TO THE ACETYLENE HOUSE LIGHTING COMPANY, OF WEST VIRGINIA.

DESIGN FOR A BURNER.

SPECIFICATION forming part of Design No. 28,649, dated May 17, 1898.

Application filed January 5, 1898. Serial No. 665,701. Term of patent 14 years.

To all whom it may concern:

Be it known that I, ERNEST UNGER, a citizen of the United States, residing at New York, in the county and State of New York, have 5 invented and produced a new and original Design for Burners, of which the following is a specification, reference being had to the accompanying drawings.

Figure 1 is a perspective view showing my 10 new design, and Fig. 2 is a side elevation of the same.

As shown in the drawings, the leading or material feature of my design consists of the gas-chamber A, bent or curved to such a degree that the cylindric projections B, carried 15

by the top C of the chamber and holding the tips D, will be inclined toward each other.

Having described my invention, what I claim as new, and desire to secure by Letters Patent, is—

The design for a burner, as herein shown and described.

In testimony whereof I have signed my name to this specification in the presence of two subscribing witnesses.

ERNEST UNGER.

Witnesses:

W.M. HERBERT KING,
GEO. E. COUSE.
